United States Patent Office.

GEORGE E. MARSHALL, OF LAUREL, INDIANA.

Letters Patent No. 95,365, dated September 28, 1869.

IMPROVEMENT IN BLEACHING PAPER-STOCK.

The Schedule referred to in these Letters Patent and making part of the same.

To all whom it may concern:

Be it known that I, GEORGE E. MARSHALL, of Laurel, in the county of Franklin, and State of Indiana, have invented certain new and useful Improvements in the Manufacture of Paper-Stock; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to the manufacture of paper-stock; and

The invention consists in so arranging a cover and fan as to create a current that shall gather the chlorine-gas that is evolved in the bleaching-process, and return it to stock, as hereinafter explained.

Figure 1 is an end elevation of an apparatus adapted for carrying out my invention.

Figure 2 is a vertical section of the same, on the line $x-x$ of fig. 1.

Figure 3, a horizontal section, on the line $y-y$ of fig. 2.

It is well known that in bleaching paper-stock in the ordinary rag-engine, in order to produce a quick action of the chlorine, it is necessary or usual to add to the chlorine-solution either an acid, or to apply heat, and that a large portion of the chlorine-gas escapes, and passes off into the atmosphere, and that thus a loss is effected, besides rendering it very unpleasant, and at times impossible for the workmen to remain in the room, the inhalation of the chlorine-gas being very injurious.

Efforts have been made to retain this gas in the rag-engine by a close-fitting cover; but this is objectionable for several reasons, more especially because it prevents the operator from having access to the material, which is necessary, in order to stir it, and prevent portions from accumulating in the corners, and thus failing to be operated upon, and bleached regularly and evenly.

My invention is intended to obviate all these difficulties, and I accomplish it as follows:

I take the ordinary rag-engine or other bleaching-tub, as represented by A, and build over it a cover, B, which may be of the form represented in the drawings, or of any other suitable form.

This cover should extend out beyond the tub A, more or less all around, and it has located at its apex or top a fan, C, so arranged as to suck a strong current from the outside inward, under the cover, into its case, and expel it thence through a tube, D, which extends from the fan-case, down into the tub or engine A, as represented in the drawings.

Any of the usual styles of fan or blower may be

used, it, of course, being arranged to draw the air in under the cover B, and expel it thence through the tube D.

With an apparatus thus arranged, it will be obvious that the chlorine-gas, as it rises from the engine, instead of passing off into the surrounding atmosphere of the room, will be drawn inward by the incoming current of air, and will be drawn with it into the fan, and from thence, be driven back into the solution again, thus accomplishing the twofold purpose of preventing its waste, and, at the same time, enabling the operatives to stand near the engine or tub without inhaling the gas.

In order to have more perfect control of the returning gas, I connect to the end of tube D, where it enters the tub A, a section of tube I, that is movable, being journalled at its ends, so as to be turned like a shaft.

From the side of this tube I there projects laterally a series of small pipes or nozzles, a, as shown in figs. 2 and 3, and there is a lever, l, attached to the tube I, so that the pipes a may have their points lowered to deliver the inflowing current of gas into or under the fluid and stock, or raised, as shown in dotted lines in fig. 2, to deliver the gas upon the stock above the surface of the solution, as it is being operated upon by the cylinder of the engine.

It is obvious that the cover B may be mounted on stationary supports, as represented in the drawings, or it may be arranged so as to be raised or lowered, as occasion may require, in which case the tube D would be made with a sliding joint, or of flexible material.

In any event, the sides of the cover B should extend down far enough to be sure that the inflowing current of air shall take up, and carry in all or nearly all the gas as it rises from the engine or tub, and, if necessary, there may be curtains or movable sides arranged to extend down as far as required, so that they can be adjusted or removed at pleasure.

The tube D, instead of entering at the ridge, may be arranged to enter through the bottom, or it may extend all around, or be coiled over the bottom, and provided with a series of minute openings to discharge the gas and air into all parts of the solution, and thus cause it to impregnate the mass thoroughly, the escaping gas also serving to stir up and thoroughly mix the mass, and thereby insure an even bleaching of the stock.

In this way the necessity of hand-stirring may be avoided.

The application of my invention may be varied greatly, without departing from its principle or mode of action, the accompanying drawing illustrating but one of many forms of apparatus for applying it.

It is also obvious that my invention is applicable to

the bleaching of other materials as well as paper-stock, such as cloths, and all similar articles.

Having thus described my invention,

What I claim, is—

1. Gathering the escaping gases evolved from the bleaching-solution, and conveying them away by an inflowing current of air, produced by a fan or equivalent means, substantially as described.

2. The utilization of said gases, by returning them to the tub or reservoir, substantially as described.

3. The combination of a bleaching-tub or reservoir, a receiver or cover, and a fan or its equivalent, substantially as and for the purpose set forth.

4. The adjustable delivery-pipes *a*, arranged to receive and deliver the gas, either within or above the fluid or solution, as set forth.

GEO. E. MARSHALL.
